UNITED STATES PATENT OFFICE.

LEWIS MILLER, OF AKRON, OHIO.

HARVESTER.

SPECIFICATION forming part of Letters Patent No. 293,345, dated February 12, 1884.

Application filed June 2, 1883. (No model.)

To all whom it may concern:

Be it known that I, LEWIS MILLER, of Akron, county of Summit, and State of Ohio, have invented a new and useful Improvement 5 in Harvesting-Machines, of which the following is a full, clear, and exact description, reference being had to the accompanying drawings, making part of this specification.

My invention relates to that class of grain-binding harvesters in which the grain is bound upon an inclined elevating-table arranged on the platform side of the driving-wheel; and it consists in a novel construction and arrangement of the curved angular bracket, through 15 which the frame of the machine is connected with and supported upon the drive-wheel axle; in a novel construction of the chairs supporting the elevated end of the inclined binder-frame and table, and of bracing the platform-frame through said binder-frame and chairs, and in certain details of construction and arrangement, hereinafter described.

In the accompanying drawings, Figure 1 is a perspective view, taken from the front and 25 stubble side of the machine, of so much of a harvesting-machine as is necessary to show my improvements. Fig. 2 is a perspective view of the forward chair and tongue-socket, and Fig. 3 is a similar view of the rear chair 30 and gear-plate or bracket.

A and A' represent the main transverse sills of the main and platform frame, to which the cutting apparatus, grain-wheel, and platform rake or carrier are applied in any usual or 35 preferred manner. Upon the stubble ends of these sills, with its elevated side in close proximity with the driving-wheel, is secured the inclined binder-frame, composed of longitudinal tubular rods or bars B and B' and suitable 40 transverse bars, C C', rigidly connecting the tubular bars B and B', said frame supporting the inclined binder-table interposed between the platform and the driving-wheel. The forward sill, A, has the angular axle bracket or 45 sector D D' secured to it by means of bolts or other suitable fastenings, for rigidly uniting its horizontal arm D' to the lower face of said sill. This horizontal arm extends well under the sill and binder-frame, and is, by preference, made tapering to its end, as by such 50 formation it is adapted to be firmly secured to

the sill for upholding the latter and the platform and binder frames, and unnecessary weight of metal is avoided. Its upright curved arm D is formed in one piece with the horizontal arm, and is curved in the arc of a circle, of which the secondary or sprocket-wheel shaft a' is the center, and has an axle block or sleeve, E, mounted upon it, to which the main drive-wheel axle a is rigidly secured, the arm 55 D moving up and down in said box or sleeve E as the height of the main frame is adjusted.

Upon the drive-wheel end of the sill A is secured a chair, G, (shown detached in Fig. 2,) and provided in its upper end with a seat, 60 g, for the forward end of the upper longitudinal bar, B, of the binder-frame, which may be secured therein in any suitable manner. A second chair, H, (shown detached in Fig. 3,) is secured to the rear sill, A', and serves to 65 support the rear end of the bar B. The primary purpose of chairs G and H is to uphold the outer upper side of the inclined binder-frame and table at the desired height; but to 70 economize space and cost of construction, and to avoid unnecessarily multiplying parts, the chair G is provided with a socket, g', in which the rear end of the pole or tongue F is secured by a pivot at f, permitting its vibration to accommodate the adjustment of the frame in 75 height or the rocking of said frame on its driving and carrying wheels. It is also provided at g' with a cylindrical shield, guard, or cover for a worm-wheel, h; at g' with a bearing for the shaft k' of said wheel, and at g' with a 80 sleeve-covering for a shaft, k', having a worm or screw, k'', for actuating said worm-wheel and its shaft in effecting the adjustment of the main frame on the driving and carrying 85 wheels.

The chair H, like the chair G, has a seat at h for the tubular frame-bar B, and is provided at k' k'' with tubular bearings for the secondary or sprocket and bevel wheel shaft a', above referred to, and at k' with a sleeve-bearing for the first longitudinal and main shaft of the binder mechanism, and from which motion is imparted to all the operative parts of the machine. The chairs G and H have suitable feet or flanges, through which they 90 are bolted or otherwise firmly secured to the platform-sills, and the tubular bar B is in like 95

manner secured in seats in their upper ends. The bar B' is bolted directly to the sills A and A', or to suitable brackets or socketed plates thereon, and the two longitudinal bars B and B' being rigidly connected by the inclined 5 transverse bars C C', as explained, said inclined binder-frame, in connection with the chairs G and H, is made to form a strong angular brace for stiffening and strengthening 10 the platform sills or frame, which are necessarily extended in length to accommodate and support the inclined binder-frame upon their inner ends. A brace, L, extends from the upper end of the chair G, or from the bar B, connected therewith, to the upper end of the arm D 15 of the axle bracket or sector, for stiffening and preventing lateral swaying or vibration of the latter, and a second brace (indicated at L') may also be employed, if desired, extending 20 from the bracket H forward to the arm D, for further stiffening and supporting the latter; and underneath the bevel-gears on the shaft a' and the longitudinal shaft driven therefrom is secured a board or plank, M, which extends 25 longitudinally between the bars or sills A and A'. This board may be let into the lower faces of the sills or otherwise rigidly secured to said sills, so as to be flush on its lower face with the lower faces of said sills, and serves 30 not only as a guard for the gearing referred to, but also, in connection with the binder-frame rigidly secured to the upper faces of the sills, to materially stiffen and strengthen the connection between said sills, which, aside from 35 said parts, are connected in any usual or preferred manner. The sprocket-wheel on shaft a' for actuating the latter is actuated through an endless chain from a sprocket-wheel on the hub of the drive-wheel, (not shown,) and the 40 curving of the standard D in the arc of a circle of which shaft a' is the center serves to hold said shaft a' and its sprocket-wheel always at the same distance from their driving-shaft or sprocket-wheel under any and all adjustments 45 of the height of the frame, thereby maintaining a uniform tension of the driving-chain referred to.

In the class of machines described, where the weight of the binder-frame and mechanism is thrown upon the inwardly-extended 50 platform-sills, as explained, it becomes important to stiffen and strengthen the latter as far as practicable by proper bracing, in order to avoid making the machine unnecessarily heavy and cumbrous, and this result is effect- 55

ually attained by the arrangement of the binder-frame and its supporting-chairs and the manner of bracing the axle-bracket and the platform-sills therefrom, hereinabove described.

60

Parts of the machine not particularly described may be constructed and arranged as described in other applications filed by me, or in any suitable or preferred manner.

Having now described my invention, what I claim as new is—

1. The curved and angular drive-wheel axle-bracket connected by its horizontal arm with the forward platform-sill, in combination with a brace supporting its upper end and the axle block or sleeve adjustable on said bracket, substantially as described.

2. The curved angular axle-bracket having its horizontal arm rigidly connected with the platform-sill, in combination with a chair supporting the upper end of the inclined binder-frame, and a brace connecting said angular bracket and chair, substantially as and for the purpose described.

3. The combination, with the transverse grain-platform sills A and A', of the inclined binder-frame and the chairs supporting the upper end of said inclined frame, substantially as and for the purpose described.

4. The combination, with the forward platform-sill, of the chair G, forming a support for the upper end of the inclined binder-frame, and a tongue-socket, substantially as described.

5. The chair G, forming a combined binder-frame support and tongue-bracket, and provided with the shields or guards and bearings for the mechanism for adjusting the frame, substantially as described.

6. The combination, with the platform-sill, of the chair H, provided with a seat for the upper longitudinal bar of the inclined binder-frame, and with bearings for the secondary or bevel-wheel shaft and counter-shaft, substantially as described.

7. The combination, with the platform sills or frame, of the chairs G and H, the inclined binder-frame secured to said sills and chairs, the angular axle-bracket D, and the braces L' and M, all substantially as described.

In testimony whereof I have hereunto set my hand this 23d day of April, A. D. 1883.

LEWIS MILLER.
